PICTURE BUILDING SET

Joyce Green Smith, Egg Harbor City, and Willard
Lindsey Foehl, Audubon, N. J.

Application July 19, 1933, Serial No. 681,214

7 Claims. (Cl. 46—37)

Our invention relates to improvements in picture building devices or means and my object is to provide an attractively practical, and complete, cheap and conveniently made and usable new article of manufacture, in a home ornamenting, amusement giving, and art educative picture building set or outfit that is also applicable to advertising or other commercial purpose. It may, for instance, be used to make up composite "set-up" pictures of various figures, objects or goods, for temporary visualization or guidance, or permanent record, say of window displays, or photographic copying for illustrations, etc. It is also adaptable to use by various publications in connection with printed pictures from their columns, say of figures from comic strips, which might be assembled by readers in competitions for prizes offered for the best composite picture made in these building sets, furnished free or as premiums with the journal's advertisement thereon.

We attain these objects by the means illustrated in the accompanying drawing, in which:

Figure 1 is a rear plan of a picture framing front sheet of transparent material with a viewing panel in center and printed margin rolled backward.

Fig. 2 is a vertical cross section of Figure 1.

Figure 3 is a rear plan of a picture assembling backboard with bevelled edge, designed to set against the picture framing front sheet shown in Figures 1 and 2 and be engaged by the rolled back margin of same.

Figure 4 is a vertical cross section of Figure 3.

Figure 5 is a vertical cross section showing said front frame sheet and backboard assembled without a picture between them.

Figure 6 shows in plan a sheet of paper or like material with pictures of various objects printed thereon and perforated in outline, to break apart by hand and with soft deckled-edge.

Figure 7 is a front plan of an assembled frame front sheet and backboard showing a picture built on said backboard by overlapping superposed rearrangement of depicted objects broken out of picture sheet shown in Figure 6.

Figure 8 is a plan of a modified form of construction with a flat front sheet of transparent material and backboard assembled thereto by bolts inserted through holes therein.

Figure 9 is a vertical section of Figure 8, showing means of assembly by bolts and nuts, with picture included as in Fig. 7.

Similar numerals refer to similar parts throughout the several views.

Our picture building set or outfit is comprised

preferably of: a frame forming front sheet 1 of transparent celluloid or like material which has a picture showing central panel 2 that is surrounded by a framing margin, painted or printed or otherwise made, for opacity and advertising surface, 3, that is rolled back, as 4, to form tubular resilient flanges extended rearwardly along each side of said frame sheet; a stiff and opaque sheet of pasteboard or like material, 5, with bevelled edges, 6, forming a backboard to build pictures upon which is adapted by size and edge formation to fit within the rolled-back side flanges 4 of the front frame sheet 1, against the rear face of frame sheet 1 and its central viewing panel 2, and be held there by said resilient side flanges 4 engaging its bevelled edges 6; and a plurality of outline cut pictures of various objects, as 7, preferably supplied in printed sheets, 8, with each depicted object perforated or semi-perforated in outline to permit breaking or tearing it out by hand, without necessity of scissors, knife or other tool, and also give a soft deckled, artistic outline to the depicted object which effects a natural and pleasing blending with any background upon which it may be placed.

In a modified construction of the outfit the front frame member of transparent material may be replaced by a flat sheet 10 of glass, celluloid or the like with painted or otherwise formed frame margin, 11, and a bolt hole, 12, at each corner of the central picture panel, coinciding with holes, 13, in a backboard 14; thus permitting assemblage of backboard to frame front by means of four rosette-headed bolts, as 15, with rear nuts, 16, thereon. Edge filling layers of strip paper, 20, equalize bolt strain.

The outline cut pictures of various objects, as 7, may also in modified forms of the outfit be furnished individually; or in sheets with gummed backs, 8A, to facilitate exact assemblage in group composition. With adhesive component pictures the frame proper, as shown in Figure 1, might be more cheaply made of springy sheet metal with center opening 2 punched out and the opening covered by a sheet of thin transparent material, as indicated by dotted line 17 in Fig. 1, pasted over the panel opening inside the frame.

To operate our picture building set or outfit in the preferred form, Figures 1 to 6 inclusive, the user first places the backboard 5, with bevelled edge upward, upon a table or other rest; then, first selecting and breaking from a picture sheet, as 8, such depicted objects, as 7, as are desired, proceeds to build upon the back-

board 5 in overlapping superposition in any desired arrangement the various pictorial components, thus achieving both a new and attractive arrangement of parts and an appealing natural effect of depth and background distance that is due to the method of building the picture in a sequence of adjoining but distinct facial planes, or layers of components. The picture building completed, the frame front sheet 1 is then laid upon the same and backboard 5, the rolled back side flanges 4 of frame sheet 1 contacting the bevelled edge 6 of backboard 5, and the frame pressed downward by user's fingers until resilient flanges 4 snap over the bevelled edge of the backboard, the assembled component pictures being at the same time pressed between the under surface of frame sheet 1 and the backboard 5 and held in their assemblage on the latter.

Many who have not the technical ability to personally produce, by painting or otherwise, a good pictorial representation of any object, but nevertheless possess considerable artistic taste, may by means of these completed individual pictures used as component parts and so easily handled, produce a very attractive art composition which expresses with great individuality, because no two of these compositions are exactly alike, their innate sense of the beautiful and originality of conception. Our picture building set is, therefore, a medium of artistic expression which meets a need of many people. It also furnishes a complete, framed picture of original design that is of decorative value and personal interest, which latter may be intensified by the inclusion of home photographs in the art composition. A backstay, as 18, and hanger tag, as 19, on the back of backboard 5 as shown in Fig. 5, may be used to set up on mantel or hang on wall the completed picture. It will be understood that several modifications or variations of parts may be made without departing from the spirit of the set.

We claim:

1. A picture building set comprised of a frame, a transparent front in said frame, a detachable backboard in said frame normally contacting said transparent front, means for holding said backboard against said transparent front, and a plurality of outline cut pictures of various objects adapted to assembly by overlapping superposition on said backboard and each other between said backboard and said transparent front.
2. A picture building set comprised of a frame, a transparent front in said frame, a detachable backboard in said frame normally contacting fully the back surface of said transparent front, means for holding said backboard against said front, and a plurality of outline cut pictures of various objects with dried adhesive on the backs thereof assemblable in overlapping superposition

on said backboard and each other between said backboard and said transparent front.

3. In a new article of manufacture, a picture building set comprised of a frame having resilient inturned edges, a transparent front in said frame, a detachable backboard in said frame normally contacting said transparent front, and a sheet having depicted thereon a plurality of pictures of various objects adapted to detachment from said sheet and assemblage into overlapping superposition on said backboard between said backboard and said transparent front by flexing said resilient edges of the frame upon said backboard.

4. In a new article of manufacture, a picture building set comprised of a frame having resilient inturned edges, a transparent front in said frame, a detachable backboard in said frame normally contacting said transparent front, and a picture upon paper-like material assembled by superposition on said backboard by flexing said resilient edges of the said frame upon said backboard and held in position of assembly by the pressure induced by said resilient edges between said backboard and said transparent front.

5. In a new article of manufacture, a picture building set comprised of a frame having resilient inturned edges, a transparent front in said frame, a detachable backboard in said frame normally contacting said transparent front, and a plurality of pictures of various objects adapted to assemblage in overlapping superposition on said backboard between said backboard and said transparent front by flexing the resilient edges of said frame upon said backboard.

6. In a new article of manufacture, a picture building set comprised of a backboard having a bevelled edge; a plurality of pictures adapted to assemblage upon the said backboard in overlapping superposition, and a frame front member having a transparent center panel and inturned resilient edges superposed upon said pictures and backboard and held against same by the pressure induced by the engagement of said resilient edges with the bevelled edges of the said backboard.

7. In a new article of manufacture, a picture building set comprised of a backboard having a bevelled edge, a plurality of pictures on paper-like material adapted to assemblage upon the said backboard, and a frame member having a transparent center panel and resilient inturned edges superposed upon said pictures and backboard and held against same by the pressure induced by the engagement of said resilient edges with the bevelled edge of the said backboard.
